UNITED STATES PATENT OFFICE.

FRANK B. ELLIOTT, OF BELLE PLAINE, KANSAS.

RAIL JOINT.

Application filed November 10, 1922. Serial No. 600,044.

To all whom it may concern:

Be it known that I, FRANK B. ELLIOTT, a citizen of the United States, residing at Belle Plaine, in the county of Sumner and 5 State of Kansas, have invented certain new and useful Improvements in Rail Joints, of which the following is a specification.

My invention relates to rail-joints adapted for use on steam railways, electric rail- 10 ways, and the like, and the present invention is an improvement over my rail-joint disclosed in U. S. Letters Patent No. 1,013,002, granted December 26, 1911.

The object of the present invention is to 15 retain the resilient feature of my patented rail-joint, but instead of making the same in one piece as formerly, I now make the rail-joint in two pieces which can be manufactured and applied to the rails more quickly 20 than the said one-piece rail-joint.

In order that the invention may be fully understood, reference will now be had to the accompanying drawing, in which:

Fig. 1 is a perspective view of the rail- 25 joint ready to be applied to two abutting rails.

Fig. 2 is a side elevation of the rail-joint applied to the rails.

Fig. 3 is an enlarged, irregular cross section 30 on line III—III of Fig. 2.

In carrying out the invention, I provide a rail-joint member comprising a base 2, a brace 4, a wing 6, and a seat 8. The base 2 is considerably wider than the bottoms A 35 of the abutting rails B, so that when the rail-joint member is applied to said rails B and secured to ties C by spikes D the rails will be reliably secured from spreading apart or turning over. The wide base 40 2 also presents a broad bearing surface to the underlying ties C, so that the longitudinal margins 10 will not sink or cut into said ties C and thus damage the same.

The brace 4 is formed integral with the 45 base 2 near one of the margins 10 and inclines upwardly and inwardly to the seat 8, which forms a resilient connection between the brace 4 and the wing 6 for a purpose which will hereinafter appear. The 50 wing 6, which lies against the rail webs E, extends from the top of the adjacent flanges F to the adjacent undersides of the balls G of the rails and is made somewhat thicker than the rest of the rail-joint member to 55 form, in conjunction with the brace 4, a substantial support for the seat 8, so that

the latter will form a substantial support to the balls G and the weight of a car or train running over the rails B.

The other member of the rail-joint comprises a plate 12 adapted to lie against the sides of the webs E opposite the sides engaged by the wing 6. The plate 12 is, preferably, of the same length as the wing 6 and extends from the top of the adjacent flanges F to the undersides of the balls G to coat with the seat A in supporting said balls G. The upper margin of the plate 12 is bent outwardly at an angle to provide a stiffening flange 14, which lies beneath and provides a relatively broad seat for the adjacent undersides of the balls G.

The brace 4, the wing 6 and the plate 12 have registering holes 16 for the passage of bolts 18 provided at their threaded ends 75 with nuts 20 which abut washers 22 each of which has a bevel side 24 to lie against the inclined side of the brace 4.

When the rail-joint is applied to the abutting rails B and the nuts 20 are tightened 80 upon the bolts 18, the brace 4 and the wing 6 are forced towards each other and their tendency to spring apart exerts sufficient pressure on the nuts 20 to lock the same from unscrewing and becoming loose on the 85 bolts 18, unless a wrench is used.

By making the rail-joint in two parts as shown and described it can be rolled or cast and easily applied to the abutting rails, not only reliably holding the same firmly 90 together and upon the ties, but owing to the resilient feature constitutes a nut lock as above pointed out.

From the foregoing description it will be understood that I have produced a novel 95 rail joint which is strong and durable and well adapted for the purpose intended, and while I have shown the preferred construction of the device I reserve the right to make such changes as properly fall within the 100 spirit and scope of the appended claims.

Having thus described my invention, what I claim and desire to secure by Letters Patent, is:

1. In a rail joint, a base adapted to underlie the bottoms of two abutting rails, an inclined brace extending upwardly from one side of said base, a wing spaced from said brace and adapted to lie against the webs of the rails, a seat resiliently-connecting the upper portions of the brace and said wing, and bolts extending through the rails, the

brace and the wing to secure the joint to the rails and force the free portion of said brace towards the wing to create a nut-lock action on the bolts, substantially as described.

2. A rail joint comprising a base adapted to underlie the bottoms of two abutting rails, an inclined brace extending upwardly at an angle from said base adjacent to one of the longitudinal margins thereof, a wing spaced from said brace and adapted to lie against the webs of the rails, a seat resilient-

ly-connecting the upper portions of the brace and said wing so that the former may be sprung towards the latter and create a nut-lock action on bolts passing through the rails and the joint to secure the latter to the former.

In testimony whereof I affix my signature, in the presence of two witnesses.

FRANK B. ELLIOTT.
